BUILDING CONSTRUCTION

Louis Justement, Bethesda, Md.

Application February 16, 1934, Serial No. 711,508

4 Claims. (Cl. 72—118)

My present invention relates to the building art, and has particular reference to partition constructions.

The heretofore utilized types of partition constructions include ordinary plastering, and plaster board installations. The plastering, as ordinarily used in building construction, is an expensive operation and takes a great deal of time, as at least two coats are required; it introduces vast quantities of moisture which must be allowed to dry out before any finish can be applied; it requires scaffolding thereby interfering with the work of other trades; it is the dirtiest operation in building construction, and provides a residue of vast quantities of rubbish which must be hauled away.

Moreover, the plaster is subject to damage by frost, thus requiring temporary window enclosures and heat when it is applied in winter; it is not only very easily damaged, but is also expensive to repair.

When the plaster is applied to wood studding in frame construction, it becomes subject to strains caused by wood shrinkage, which produce numerous cracks and other unsightly conditions; moreover, plaster is usually applied on wooden lath, and thus offers poor fire resistance, as the use of metal or other incombustible lath is too expensive for ordinary use.

The application of plaster board instead of plaster has therefore been advocated, as the board is manufactured under factory conditions and constitutes an excellent material capable of overcoming practically all the disadvantageous features incident to the use of ordinary plaster. There are two standard types of board now in use, plaster-board lath in small sheets, and plaster board in large sheets, usually about four by ten feet, the lath being merely an incombustible lath to which ordinary plaster is applied, and the sheet being adapted for securing to wood studding by nailing.

The plaster board sheet, while greatly preferable to ordinary plaster, has heretofore also had certain disadvantages. Since the wood studding is rarely absolutely uniform in size or absolutely straight, the board is subjected to distortive stresses which impair its application and mar its appearance. The jointure of adjacent boards is normally covered with canvas, and the nail heads at every stud must be countersunk and covered with plastic material; moreover, the walls must be papered to conceal the joints and nail heads, as painting does not produce a satisfactory finish unless the walls are first covered with canvas.

If partitions of incombustible material are desirable or are required by law, the use of wood studs, which are necessary for receiving the securing nails, renders plaster board unsuitable. It is difficult, moreover, to remove or repair one board without refinishing the entire room, and there is but little salvage value in dismantled boards.

It is the principal object of my invention to provide an improved plaster board construction that is easily applied, and that overcomes the objections heretofore found in the use of board.

To this end, I have devised a concealed fastening construction which is applied to plaster board and to studding at the factory, and thus permits snapping the board into place with a minimum of cutting, the resulting wall being with finished surface, ready for papering or painting, if desired.

A further object of my invention is to arrange the boards and studding so as to provide a removable partition of which the various parts may be used over and over again.

With the above and other objects and advantageous features in view, my invention consists of a novel arrangement of parts more fully disclosed in the detailed description following, in conjunction with the accompanying drawings, and more specifically defined in the claims appended thereto.

Referring to the drawings,

Fig. 1 is an elevation of a typical partition embodying my invention;

Fig. 2 is a vertical section on the line 2—2 of Fig. 1;

Fig. 3 is a horizontal section on the line 3—3 of Fig. 2;

Fig. 4 is a sectional detail illustrating the intersection of two wall surfaces;

Fig. 5 is a section on the line 5—5 of Fig. 1;

Fig. 6 is a section similar to Fig. 2, but illustrating a steel channel stud type of construction;

Fig. 7 is a section on the line 7—7 of Fig. 6;

Fig. 8 is a sectional detail of a wall intersection; and

Fig. 9 is a section similar to Fig. 5, but illustrating the use of wood jamb or trim with this type of construction.

I have found it advantageous to use wall board of plastic or fibrous material, equipped with anchor clips which are inserted in the material before final hardening or set, which anchor clips are entirely concealed in the wall, partition or ceiling after erection, whereby a finished appearance is obtained without need for covering by paper, paint, or the like, the boards being pro-

vided with notches or slots which receive suitable studs having corresponding projections, and having the edges thereof equipped with a compressible material such as felt, for example, to 5 tightly seal the joints and prevent sound transmission. I have also found it desirable to use partition studs made of plastic, cementitious, or fibrous material, which contain one or more wires that extend beyond the upper and lower ends 10 of the studs and serve to reinforce the stud and to anchor the stud to other structural members at the top and bottom thereof. These novel arrangements are more fully described herewith by reference to the accompanying drawings, in 15 which like reference characters designate the same or similar parts.

In the drawings, a typical partition such as shown in Fig. 1 includes a cornice mould 5, a base 6, vertical joints 7, and usually a door 8. 20 The construction of partitions of this type includes the securing of top channels 9 and bottom channels 10 to the floors 11, by suitable means such as spaced bolts or anchors, a strip of sound deadening material 12 being preferably inserted 25 between the channels and the floors. These channels have circular slots 13 at spaced intervals, usually one inch, whereby the positioning of the bottom channel with one slot in vertical alignment with a corresponding slot in the upper 30 channel also aligns the other slots.

Studs 14 are now inserted between the channels, having wire reinforcements 15 which extend a short distance beyond the stud end, usually about $\frac{1}{4}$ inch, the lower end of the wire being 35 dropped into the slots in the bottom channel and the upper ends being received in the slots of the upper channel, which may be slotted, made in sections, or otherwise arranged to facilitate the insertion and the retention of the upper wire 40 end. The studs may be of any incombustible plastic material having adequate strength and sound resisting qualities, such as for example aerated concrete or plaster. At spaced intervals, usually 2 or 3 inches, concealed metal anchors 45 or inserts 16 are provided, adapted to cooperate with plaster board fasteners, as hereinafter described. If desired, resistance to sound transmission may be increased by using layers of felt 17 or the like.

50 The plaster boards 18, which have heretofore been made four feet wide, are preferably of a width to suit normal stud spacing, which may be fourteen or sixteen inches on centers, additional sizes being provided in multiples of two inches to make possible any length of wall without cutting. 55 The edges on each side of the board are offset as shown in Figs. 3 and 4, and one face is provided with concealed metal inserts 19, which are made to align with and to fit over the metal anchors 60 or inserts 16 of the studs. The anchor 16 is inclined to provide a gravity lock, but the anchors and inserts may be modified as indicated at 20 and 21 to utilize a spring action instead. In either case, the fastening devices are entirely concealed and the inserts in the plaster boards are flush with the surface, thus facilitating handling and packaging.

In installing the boards, the edges of the boards lap to produce a firm lock, as indicated in Fig. 3; 70 a small round strip 22 of compressible material such as felt is preferably secured to the edge which does not have the concealed insert, at the factory, so that the snapping of each board in place compresses the felt to tightly seal the 75 joint. If desired, the sides of the studs may be

covered by a very thin layer 23 of felt or other suitable material to resist vibration and sound transmission.

The novel construction is readily modified for use with a pressed metal door jamb or trim, such as shown in Fig. 5. The stud 24 is made larger, and has a plurality of reinforcing wires 25, usually three or more, to provide additional strength, and has openings 26 to receive bolts 27 for anchoring the door jamb and trim for one side. 10 The trim for the other side is snapped in place by clips 28 of standard type.

A less expensive construction is illustrated in Fig. 6, this arrangement requiring less precision in manufacturing and not so close a coordination 15 between the studs and plaster boards; it is however, less fire proof and less sound proof. In this arrangement, channel shaped studs 29 of pressed metal, preferably steel, are locked to the top and bottom channels 9 and 10. Steel clips 30 are embedded in the plaster board, and are spaced at appreciable intervals, the clips being found to fit tightly against the inner surfaces of the channels, as indicated in Fig. 7. The joints between boards may be lapped, as shown 25 in Fig. 3 and the lower part of Fig. 7, or may be bevelled, as shown in the upper part of Fig. 7.

The bevelled joint may be utilized in the construction shown in Fig. 3, as both the bevelled and the lapped joints require clips or inserts on 30 only one side of the board. Fig. 8 shows the two types of joints as applied to the intersection of two walls.

Instead of using steel door jambs, a construction such as shown in Fig. 9 may be utilized, having 35 a wood buck 31 secured to two channel studs 29 which are placed back to back and spot welded. The wood jamb 32 is fastened to the wood buck 31 and the wood trim 33 is then applied to cover the plaster board, wood buck, and jamb. 40

It is thus evident that an extremely light weight partition of incombustible material, lighter than a plastered wood stud partition, is provided; that the partition is quickly erected, without requiring precautions or shelter in cold weather; that a saving in floor space is obtained, as the partition has less thickness; that the cost is lower, both for materials and for installations; that the finished partition may be used without requiring papering or painting, and that the partition 50 is readily dismantled, the parts being ready for use again, except for such cleaning as is needed.

The novel construction has other advantageous features, in that an ideal low cost suspended ceiling is obtained by securing the studs horizontally to the bottom surface of the floor construction; also, an inexpensive but highly effective wall-furring is obtained by using the studs against exterior masonry walls. Moreover, plaster cracking due to shrinkage is readily overcome 60 by having all floor joists bear against steel or other non-shrinkable girders, the upper and lower channels of the described construction then being secured to the bottoms of the usual wood beams. The use of the described construction 65 for partitions, ceilings, and for wall-furring, as described, eliminates all plastering and the disadvantageous features thereof. If desired, any fibrous or composition wall board may be used instead of plaster board.

While I have described specific constructional embodiments of my invention, it is obvious that desired changes in the form, in the dimensions, and in the materials used, and in the spacing and arrangement of the interlocking parts, may 70 75

be made to suit the requirements for different installations, without departing from the spirit and the scope of the invention as defined in the appended claims.

5 I claim:

1. An article of manufacture, comprising a wall board having an anchor clip imbedded therein and extending through one face at one edge thereof, one edge of said wall board having a strip of compressible material secured thereto, the edges of said wall board being stepped said clip having a portion spaced from and parallel to the board surface.
- 10 2. An article of manufacture, comprising a wall-board, having interlock edges and projecting spaced anchor clips on one edge, said anchor clips being spaced from and extending parallel to the board surface these anchor clips being spaced so as to be staggered on alternate wall-boards,
- 15 20 whereby the projecting anchor clips will fit in the space between the interlock edges when the wall boards are placed edge to edge, and a strip

of compressible and elastic material secured on one edge.

3. In combination, a stud construction having an anchor member, a board construction having an anchor clip extending from one edge thereof and parallel to and spaced from the edge of the board construction, a second board construction, the edges of said board constructions having interlocking parts, said anchor member and clip being engageable to lock the board constructions to the stud construction.

4. In combination, a stud construction having an anchor member, a board construction having an anchor clip extending from one edge thereof and parallel to and spaced from the edge of the board construction, a second board construction, the edges of said board constructions having interlocking parts, said anchor member and clip being releasably engageable to removably lock the board constructions to the stud construction.

LOUIS JUSTEMENT.
